UNITED STATES PATENT OFFICE.

ARTHUR G. BRUNTON, OF CENTRALIA, WASHINGTON, ASSIGNOR OF ONE-HALF TO
WALTER J. WOODS, OF SEATTLE, WASHINGTON.

WORK-HOLDER FOR LATHES.

1,078,484.

Specification of Letters Patent.

Patented Nov. 11, 1913.

Application filed November 25, 1912. Serial No. 733,297.

To all whom it may concern:

Be it known that I, ARTHUR G. BRUNTON, a citizen of the United States, residing at Centralia, in the county of Lewis and State of Washington, have invented certain new and useful Improvements in Work-Holders for Lathes, of which the following is a specification.

This invention relates to attachments for lathes; and its object is the provision of an improved work-holder or attachment for a lathe wherewith various operations such as facing and boring may be accomplished upon a lathe.

15 The invention consists in a novel construction of work-holder adapted to be rigidly secured to the lathe slide-rest, as will be hereinafter described and claimed.

In the accompanying drawings, Figure 1 20 is a perspective view of an embodiment of my invention applied to the slide rest of a lathe. Figs. 2 and 3 are perspective views of the work holder shown detached, a piece of work being illustrated as attached to the 25 holder in Fig. 2.

The reference numeral 5 designates a portion of a blade bed, and 6 is a slide rest mounted thereon and having a slot 7 for the accommodation of a tool post, when required.

8 represents the handle for the cross feed screw whereby said slide rest is adjustably moved transversely of the lathe.

All of the above mentioned parts are of 35 ordinary or standard construction.

According to the present invention, I provide a plate 9 formed with a horizontal element 10 and a vertical element 11 extending downwardly from one end thereof. Provided in the plate element 10 is a plurality 40 of apertures 12 distributed throughout the same, and in the element 11 is provided a substantially vertical slot 13, as shown in the views.

45 14 represents a stirrup-plate provided near its upper end with a hole 15 and adjacent to its lower end is a slot 16. The stirrup plate serves as a clamping member to hold a piece of work as A, Figs. 1 and 2, 50 against the face of the main plate 9 by means of securing bolts 17 and 18. The former, 17, passes through the hole 15 of the stirrup plate and one of the apertures 12 of the main plate and receives a nut 19 upon 55 the threaded end of the bolt. The other

bolt, 18, extends through the slots 13 and 16 of the two plates and also through the slot 17 of the slide-rest.

The bolt 18 is screw threaded to receive nuts 20 and 21 at opposite sides of the slide rest for securing the plate 9 firmly to the latter, and another nut, 22, is screwed upon this bolt and against the stirrup plate to co-operate with the nut 19 for securing the stirrup plate in position to clamp the work between the two plates. A washer plate 18' is desirably interposed between the nut 20 and the slide rest to afford a better bearing for said nut.

A supplementary stirrup plate, like that above described and indicated by broken lines 23 in Fig. 2, may be utilized to secure work to the plate 9 through the agency of bolts 25 extending through the plate 23 and suitably disposed apertures in plate 9. Or, where the nature of the work will permit, a bolt, as 24, may serve to co-operate with the first described stirrup-plate for securing work to the plate 9.

The operation of the invention may be 80 explained as follows: Assuming the eye A' of a connecting rod A is to be bored with a boring or cutting tool carried by the spindle which is journaled in the head stock of a lathe not illustrated. The plate 9 is first 85 rigidly connected to the slide rest by the bolt 18 and nuts 20 and 21. The work, as rod A in the example, is then clamped to the plate 9 through the instrumentality of the stirrup plate, or plates. The work is then 90 adjusted to present the eye A' in axial alignment with the axis of the boring tool, as indicated by broken line x x in Fig. 1. Such adjustment is accomplished by manipulating the handle 8 to regulate the transverse 95 position of the slide-rest 6 and then raising or lowering the plate 9 after slackening the nuts 21 and 22 to permit the relative movement of the bolt 18 in the slots 13 and 16 of the respective plates.

The invention is extremely simple and affords convenient means for performing numerous operations in a lathe which have hitherto been generally done on boring machines, shapers, planes, etc.

What I claim, is:—

1. The combination with the slide rest of a lathe, of a work-holder comprising a plate provided with a plurality of apertures, a stirrup plate, and bolts extending through

100

110

both of said plates for clamping work therebetween, one of said bolts also serving for rigidly securing the work holder to the slide rest of the lathe.

5. 2. The combination with the slide rest of a lathe; of a work holder comprising an apertured plate, a second plate, a nutted bolt extending through said slide rest and both of the plates, whereby the work holder is rigidly secured to said slide rest, and a bolt acting supplementary to the aforesaid bolt whereby work may be clamped between said plates.
10. 3. The combination with the slotted slide-

rest of a lathe, of a work holder comprising 15 an L-shaped plate having a slot in one of the limbs thereof, a bolt extending through the slots of the slide rest and said plate for adjustably securing the latter to said slide-rest, and means for clamping work to the 20 plate.

Signed at Seattle, Wash., this 16th day of November, 1912.

ARTHUR G. BRUNTON.
